UNITED STATES PATENT OFFICE.

HANS PRYM, OF STOLBERG, GERMANY.

MACHINE FOR MOUNTING PRESS BUTTONS ON CARDS.

1,407,576.

Specification of Letters Patent. Patented Feb. 21, 1922.

Application filed October 29, 1921. Serial No. 511,497.

To all whom it may concern:

Be it known that I, HANS PRYM, a subject of Germany, and residing at Stolberg, Rhine State, in the State of Prussia, Germany, have invented certain new and useful Improvements in or Relating to a Machine for Mounting Press Buttons on Cards, of which the following is a specification.

10 The invention relates to a machine for mounting press buttons on cards or the like, provided with frame plates carried by an endless chain, the lower parts of the press buttons, the cards and the upper parts of 15 the press buttons being consecutively placed on the said plates before they arrive at a press which joins together the press button parts, and consists in the press button parts and the cards being placed on the frame 20 plates, that is to say the press button parts withdrawn from the supply conduits and the cards from the card case or container, by the movement of the endless chain or of 25 the frame plates carried thereby. In that way an accurate and reliable fitting together of the press button parts and cards is ensured.

A construction according to the invention is illustrated in the accompanying drawing 30 in which—

Figure 1 is a side elevation and

Figure 2 a cross-section at the point where the press is situated for joining together parts of the press button.

35 Figure 3 is a partial longitudinal section, on an enlarged scale, through the supply conduit or channel for the upper parts of the press buttons, and

Figure 4 is a longitudinal section through 40 the supply conduit for the lower parts, whilst

Figure 5 is a front elevation of Figure 3.

Figure 6 is a cross-section through the card delivery device, and

45 Figure 7 is a plan thereof.

Two spindles 2 and 3 mounted in one frame 1, carry chain wheels 4 and 5 for an endless chain 6 constituted by links of equal size connected together by bolts. 50 Each link carries a plate 7 with pins 8 arranged at the longitudinal and transverse distances of the perforations of a press button card. To ensure efficient guiding, the plates 7 travel in grooves 9 in the frame 55 1 (see also Figure 6). Above the chain the supply channel 10 is arranged for the lower

parts, and the supply channel 11 for the upper parts of the press buttons. At their outlet ends, the channels are provided with clamping or holding devices which do not 60 allow the button parts to drop out freely. These clamping devices are constituted, for each channel, by a series of locking pins 13 and 14 (Figures 3-5) mounted on a transverse member or carrier 12 and projecting 65 into the supply channel 10 or 11. The locking pins 13 which are provided at the lower ends with grooves 13^a, are mounted in an approximately vertically adjustable manner in the transverse carrier 12, and are forced 70 by springs 15 into the channel 10 or 11 so that they prevent the lowest press button part contained in the channel, from escaping, and hold it in an oblique position in the channel, the hood or cap of the button 75 being held in the groove 13^a. The locking pins 14 are arranged in a horizontally adjustable manner and are pulled slightly into the channel in the lateral direction by spring 16, so that the press button part can- 80 not emerge at the side. Only when the locking pins 13, 14 are forced back, the press button part which is the lowest position at the moment, can escape from the channel 10 or 11.

85 Between the supply channels 10 and 11 the card container or case 17 is arranged to support a supply of the perforated cards 18 (Figures 6 and 7) which rest on a support 17^a and are elevated by springs 17^b. 19 is a 90 slide for advancing of the cards, which is advanced owing to a tappet 20 provided on the chain 6, striking, during the advance of the latter in the direction of the arrow I, an arm 21 of a double arm lever 21, 23 pivoted 95 at 22. Two rubber rolls 24 and 25, the spin- dles of which are mounted on springs, and which are driven by a toothed wheel 26, ad- vance the cards supplied to them by the slide 19. At the other side of the chain to 100 the machine frame is secured a bracket 27 into the upper end of which is firmly screwed a bar 28. Under the said bar and pivotally connected to it by bars or links 29, is a bar 30 which projects through a slot of the 105 bracket 27 and carries at its outer end a roller 31. A spring 32 constantly pulls the bar 30 into the upper position shown in Figure 6; its height can be adjusted exactly by means of a set-screw 33. On the bar 30, at 110 right-angles thereto and at a small distance apart, are mounted two plates 34 which

clamp between them and hold fast the cards supplied by the rolls 24, 25. About a vertical pin 35 a lever 36 can turn provided at right-angles with an arm 37. As soon as, during 5 the movement of the chain, a tappet 38 screwed to the chain plate 7 strikes the arm 27 at the point 39, the said arm and therefore the lever 36 will be turned sideways, and the lever will drive the roller 31, owing 10 to which the bar 30 will be laterally pulled out of the bracket 27 (see the dotted lines in Figure 7) and owing to the bars 29, turned vertically downwards.

40 is an ebonite roll (Figures 1-3) mounted 15 by means of springs immediately behind the supply channel 11 in bearings 41 of the frame 1 and constituted by several discs (one for each series of buttons) mounted loosely and in a freely rotatable manner on the spindle of the roll. It is used as a press for joining together the press button parts. Its subdivision into single loose discs is for the 20 purpose of gradually and lightly pressing the press button upper parts.

25 The working of the machine is as follows:—

The chain travels in the direction of the arrow (Figures 1 and 7), and the supply channels 10 are filled with the lower parts 30 of the press button, and the channels 11 with the upper parts. Of these channels as many are arranged side by side as there are rows of pins on the frame plates 7. The lower parts 42 which are at the outlet of the channels 10 at the discharge points, are in such 35 an oblique position that the pins 8 of the plates 7 engage by means of their offset ends, with the openings of the button caps (Figure 4) and pull them out from their holding devices 13, 14, the button caps being guided in the grooves 13^a. Each pin 7 carries therefore one lower part 42.

In the meantime the tappet 20 has moved the lever 21, 23. Owing to that, the slide 19 45 introduces a perforated card 18 with its front edge between the rubber rolls 24 and 25, and the said rolls introduce the card between the clamping plates 34. The lever 21, 23 is pulled back by a spring (not shown) 50 immediately after the sliding off of the tappet 20.

During the continued movement of the chain, the tappet 38 provided on the frame plate 7, strikes at 39 the arm 37 and by 55 means of the lever 36 and the roller 31, pulls the bar 30 out of the bracket 27, the said bar turning downwards and pressing on the card 18 held by the clamping plates 34. At the same moment however during the travelling 60 of the chain the tappet 38 arrives at a slot 43 of the bar 30 and pushes the card 18 out of the clamping plates 34. The card therefore will be pressed down by the bar 30 on the pins 8 travelling under it, with the 65 lower parts 42 mounted on them, so that

it surrounds with its holes the lower parts and continues to travel with the same to the point under the withdrawal device of the channels 11. The upper parts 44 (Figure 3) which stick there, are also in such an oblique position that the caps of the lower parts 42 moving in the horizontal direction and projecting through the holes of the card 18, engage with the cap openings of the upper parts 44 and pull the latter out of the channels 11. The two head parts 42, 44 sitting loosely on each other then pass with the card 18 between them, under the rubber roll 40 which, by the pressure of its spring controlled spindle, presses the button caps 80 into each other and thus secures them to the card. The finished cards then drop, during the continued movement of the chain over the chain wheel 5, into a collector tank.

Having now particularly described and ascertained the nature of my said invention and in what manner the same is to be performed, I declare that what I claim is:—

1. A machine for mounting press buttons on cards including a movable carrier, guides associated with said carrier and being adapted to supply the lower parts of press buttons to said carrier, means mounted on said carrier and engageable with the lower parts of the press buttons in said guides for withdrawing the lower parts of the press buttons from said guides, means associated with said carrier and actuated by said carrier for separately supplying perforated cards to the lower parts of the press buttons carried by 90 said carrier, a second set of guides for supplying upper parts of press buttons to the lower parts of the press buttons supported by said carrier, and pressing means for exerting pressure on the press button parts to 95 cause the same to be secured to said cards.

2. A machine of the kind defined by claim 1 in which the means mounted on the carrier and engageable with the lower parts of the press buttons includes pins, and holding devices cooperating with said first mentioned guides for holding the lower parts of the press buttons in oblique positions at such a distance above the carrier that the pins of the latter may engage said lower parts.

3. A machine of the kind defined by claim 1 in which the first mentioned guides are provided with a plurality of spring-controlled locking members for normally preventing the lower parts of the press buttons 120 from moving out of the first mentioned guides, said locking members being arranged in pairs, one locking member of each pair projecting into the guide from the top and the other member of the pair projecting into 125 the guide from the side.

4. A machine of the kind defined by claim 1 in which the means for supplying perforated cards to the carrier includes a sliding member actuated by said carrier, a card sup-

ply case from which the cards are moved by said sliding member, a clamping plate adapted to grasp the cards fed by said sliding member, and means actuated by said carrier for causing said plate to move toward the carrier for depositing a card carried by the clamping plate on the carrier.

5. A machine of the kind defined by claim 1 in which the means for supplying perforated cards to the carrier includes a bracket arranged adjacent to the carrier, links pivotally connected to said bracket, a clamping plate pivotally connected to said links, a lever for actuating said clamping plate to cause the same to move toward said carrier, and a tappet mounted on the carrier and engageable with said lever for causing actuation of the clamping plate.

6. A machine of the kind claimed in claim 20 5 in which the clamping plate is provided with a slot adapted to permit the passage of said tappet for the purpose of dislodging a card carried by the clamping plate.

7. A machine of the kind defined by claim 25 1 in which the means for pressing the press button parts together includes a roll formed of a number of spaced disks.

8. A machine for mounting press button parts on cards comprising a movable carrier, a magazine carrying the lower parts of press buttons, projecting members on said carrier adapted to engage the lower parts of the press buttons supported by said magazine and withdraw the same from the maga-

zine, means associated with said carrier for placing a perforated card over the lower parts of the press buttons supported by said carrier, a second magazine associated with the carrier and adapted to contain the upper parts of press buttons and to hold the same in such manner that the lower parts of the press buttons supported by the carrier may withdraw the upper parts of the press buttons from the second magazine, and means for exerting pressure on the press button parts supported by the carrier for causing the same to be clamped to said card.

9. A machine of the kind defined by claim 8 in which the carrier consists of an endless chain, and the projecting members on the carrier include pins.

10. A machine of the kind defined by claim 8 in which each of the magazines is provided with spring-controlled locking members for normally preventing withdrawal of the press button parts from said magazines, said locking members being arranged in pairs, one locking member of the pair being movable towards and away from the carrier, and the other locking member 55 of the pair being movable toward and away from the first mentioned member of the pair.

In testimony whereof I hereunto affix my signature in the presence of two witnesses.
